US00D978685S

(12) **United States Design Patent** (10) **Patent No.:** **US D978,685 S**
(45) **Date of Patent:** **** Feb. 21, 2023**

(54) **HOUSING FOR GLOSSMETER**

(71) Applicant: **PROCEQ AG**, Schwerzenbach (CH)

(72) Inventors: **Stephan Gianola**, Dornach (CH); **Bernhard Pleimer**, Reinach (CH); **Séverine Berger**, Riehen (CH); **Michael Geiser**, Zurich (CH); **Ralph Mennicke**, Uster (CH)

(73) Assignee: **PROCEQ AG**, Schwerzenbach (CH)

(***) Term: **15 Years**

(21) Appl. No.: **29/724,390**

(22) Filed: **Feb. 14, 2020**

(51) **LOC (14) Cl.** **10-04**

(52) **U.S. Cl.**

USPC **D10/46**; D10/98

(57) **CLAIM**

The ornamental design for a housing for glossmeter, as shown and described.

DESCRIPTION

FIG. 1 is a perspective view of the housing for glossmeter showing our new design;

FIG. 2 is a front side elevational view thereof;

FIG. 3 is a back side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown are included for the purpose of illustrating portions of the housing for glossmeter that form no part of the claim.

1 Claim, 7 Drawing Sheets
